HANS HILLMANN, OF DRESDEN-STREHLEN, GERMANY, ASSIGNOR TO THE HILLMAN
SYNDICATE, LIMITED, OF LONDON, ENGLAND

GLASS-BLOWING MACHINE

Application filed June 10, 1929, Serial No. 369,853, and in Germany June 22, 1928.

In the case of centrally divided blank moulds for glass-blowing machines, it is important that during the suction of the glass into the blank-mould, not only should the 5 interior space of the blank-mould be evacuated, but also care should be taken to prevent any air entering said interior from outside through the joints during the suction stage. It has already been proposed to 10 vide, in the divisional surfaces of the halves of the blank-mould, air passages from which the air entering through the joints during the suction stage is aspirated in the same way as the air from the interior space of the 15 blank-mould.

In the bottle blowing machines in which the cavity of the blank-mould and the auxiliary passages disposed in the divisional planes are connected with a common suction 20 and blowing pipe, care must be taken that the air passages situated in the joints are closed during the injection of compressed air serving to press the ball or gob of glass against the inner walls of the blank-mould, since 25 otherwise they would contain compressed air which would enter the interior space of the blank-mould through the joints, thereby counter-acting the effect of the admission of compressed air into said space. The closing 30 of the auxiliary passages is effected by providing valves or similar closing device between said passages and the common pipe serving for the evacuation of air, and for the admission of compressed air for blowing, 35 which valves or the like automatically open under suction and close during blowing.

A typical embodiment of the invention is illustrated in the drawing, in which Fig. 1, represents the blank-mould during the suction stage, and Fig. 2 the blank-mould during the admission of compressed air.

a denotes a half of the blank-mould, with the divisional surface pointing forwards, i. e. radial to the machine. Consequently 45 the divisional plane of the blank-mould lies in the plane of the drawing. *b* is the half of the neck mould, the divisional plane *x* of which may be offset by 90° in relation to that of the blank-mould *a*. *c* is an 50 air cylinder in which is movably disposed, in

known manner, a piston *d* carrying the plug *e*, on which is attached a plate *f*, having a plurality of holes *g*. The cylinder *c* is connected with an air pipe *h* which communicates alternately with the compressed air or 55 suction pipe. Each half of the neck mould is provided with a bore *i* forming, at the bottom, a valve seat *k* communicating in turn with a bore *l*. A valve ball *m* plays on each valve seat. Each of the bores *l* communicates with a passage *n* disposed in the divisional surfaces of the halves *a* of the blank-mould *a*. In the operative stage represented in Fig. 1 the pipe *b* is under a vacuum. The piston *d* being drawn downwards, 60 the plug is in its lower end position. Air is drawn in through the holes *g* so that the interior space *o* of the blank-mould is evacuated and the glass can be drawn in. In consequence of the negative pressure prevailing 65 in the cylinder *c* air can, however, also be sucked in from the passages *n* through the joints of the blank-mould in the direction indicated by the arrow, since the light valve 70 balls *m* lift at once under the influence of the vacuum. When the blank-mould has been filled with glass and the surplus glass 75 has been cut off, below the blank-mould, by the knife *p* (see Fig. 2) the air supply is reversed, so that now compressed air enters the 80 cylinder *c*. The piston *d*, with plug *e*, ascends. Compressed air acts on the ball of glass and presses it against the inner walls of the inner mould *o*. At the same time, however, the 85 valve balls *m* are forced against their seats by the influence of the compressed air, so that the compressed air cannot enter the passages and therefore cannot disturb the pre-moulding in the mould. In the embodiment 90 represented, the automatic closing devices are shewn in the form of ball valves, which are specially suitable for carrying out the invention by reason of their simplicity and reliability. This, however, does not prevent 95 the employment of closing devices similar to ball valves, for example cone valves, ring valves, plate valves and the like.

In the specified construction these closing devices are located in the neck mould itself. This, however, does not preclude their inter- 100

position into the path of the suction and compressed air, in any other way.

I claim:—

1. In a divided blank mould, for a glass-blowing machine, having passages disposed in the divisional planes, the combination of means providing a common suction and blowing space communicating with said passages and the mould cavity, and automatically acting valves disposed between said passages and said space. 70
2. In a divided blank mould, for a glass-blowing machine, having passages disposed in the divisional planes, the combination of means providing a common suction and blowing space communicating with said passages and the mould cavity, and ball valves disposed between said passages and said space for closing said passages during the blowing stage. 75
3. In a divided blank mould and neck mould combination, for a glass-blowing machine, wherein the blank mould has passages in the divisional planes and the neck mould has bores communicating with said passages, means providing a common suction and blowing space communicating with said bores and the mould cavity, and valves for automatically closing said passages during the blowing stage. 80
4. In a divided blank mould and neck mould combination, for a glass-blowing machine, wherein the blank mould has passages in the divisional planes and the neck mould has bores communicating with said passages, means providing a common suction and blowing space communicating with said bores and the mould cavity, and valves arranged to seat automatically in said bores during the blowing stage. 85
5. In a glass-blowing machine, the combination of a divided blank mould having passages disposed in the divisional planes, a co-acting divided neck mould having bores to align with said passages and a central opening to align with the mould cavity, a cylinder surmounting said neck mould to form a common space in communication with said bores and central opening, means for alternately connecting said space with a source of suction and with a source of supply of pressure air, valves arranged to seat in said bores during the air supply, a piston slid-90able in said cylinder, and a plug carried by said piston. 95
6. In a glass-blowing machine, the combination of a divided blank mould having passages disposed in the divisional planes, a co-acting divided neck mould having bores to align with said passages and a central opening to align with the mould cavity, a cylinder surmounting said neck mould to form a common space in communication with said bores and central opening, means for alternately connecting said space with a source of suction and with a source of supply of pressure air, valves for automatically closing said passages during the air supply, a piston slid-100able in said cylinder, and a plug carried by said piston, and a ported member on said plug arranged to seat on said neck mould over its central opening during the suction stage. 105

In testimony whereof I affix my signature.
HANS HILLMANN.
